Primary Examiner — Katrina A Betton(74) *Attorney, Agent, or Firm* — Lathrop & Gage LLP(57) **CLAIM**

The ornamental design for an dual display arrangement for an aircraft console, as shown and described.

DESCRIPTION

This application is also related to commonly-owned and cofiled U.S. Design patent application Ser. No. 29/400,582, entitled Display for an Aircraft Console, filed Aug. 30, 2011, U.S. Design patent application Ser. No. 29/400,579, entitled Article Holding Area for an Aircraft Console, filed Aug. 30, 2011, and U.S. Design patent application Ser. No. 29/400,572, entitled Aircraft Console, filed Aug. 30, 2011.

FIG. 1 is a top front perspective view of a dual display arrangement for an aircraft console which embodies my new and original design therefore;

FIG. 2 is a front elevational view thereof;

FIG. 3 is a top plan view thereof;

FIG. 4 is a left hand side elevational view thereof; and,

FIG. 5 is a right hand side elevational view thereof.

The broken lines in the drawings are for illustrative purposes only and form no part of the claimed design.
